BRIQUETTE MAKING MACHINE

John F. Crawford, Racine, Wis., assignor to J. I.
Case Company, Racine, Wis., a corporation

Application August 28, 1936, Serial No. 98,334

22 Claims. (Cl. 25—69)

The present invention relates to machines for forming small uniformly sized bodies or briquettes by compressing suitable comminuted material, such for example as coal, and an object 5 of the invention is to generally improve the construction and operation of such apparatus.

Further objects are to provide an improved general organization of machinery for this purpose; improved mechanism for actuating the dies in such a machine; improved mechanism 10 for feeding material to the dies and insuring a correct charge before closing thereof, and improved mechanism for ejecting finished briquettes from the dies, and which is arranged 15 to also serve to assist in the proper charging thereof.

A further object is to provide improved mechanisms and instrumentalities for the carrying 20 out of the above objects, and other objects will become apparent from the following description and accompanying drawings in which:

Figure 1 is a plan view of the general arrangement of the various units employed.

Figure 2 is a side elevation of the compressing mechanism with parts broken away.

Figure 3 is an enlarged vertical axial sectional view of the compressing device taken on the line 3—3 of Figure 1.

Figure 4 is a horizontal sectional view taken on the line 4—4 of Figure 3.

Figure 5 is a fragmentary sectional view showing in detail an automatic feed control.

Figure 6 is a sectional view of a load responsive device taken on the line 6—6 of Figure 5.

Figure 7 is a horizontal sectional view of a hydraulic relay mechanism taken on the line 7—7 of Figure 5.

Figure 8 is a vertical sectional view of a certain pump structure taken on the line 8—8 of Figure 7.

Figure 9 is an axial sectional view of certain pulley structure indicated in Figure 5.

Figure 10 is a similar view with the parts in a different position.

Figure 11 is a sectional view of the same taken on the line 11—11 of Figure 9.

Figure 12 is a detail of certain feeding mechanism indicated in Figure 4, taken on the line 12—12.

Figure 13 is a vertical sectional view taken on the line 13—13 of Figure 4.

Figure 14 is a vertical sectional view taken on the line 14—14 of Figure 4.

Similar reference characters have been applied to the same parts throughout the drawings and specification.

As seen in Fig. 1, the material to be compacted is dried in a drier D, being fed thereto as needed from a bin B, and the dried material, with its moisture content reduced to a proper amount for briquetting, is transported by a conveyer C 5 to a pulverizer P in which it is reduced to a suitable degree of fineness. The material is then taken by means of an elevator E to a hopper H from which it is fed to the compressing machine M, the finished briquettes being removed from 10 the machine to a suitable place of delivery or storage by a second elevator E'.

The specific type of drying, pulverizing, and conveying mechanisms, form no part of the present invention and it is not considered necessary to describe them further, but attention is directed to the compressing or briquetting mechanism proper, generally designated by character M.

It is to be noted in considering this mechanism that the compressing of the material obtained by 20 the disclosed apparatus is such that certain bituminous constituents thereof are expressed from the particles to serve as a binder, no other binder being necessary or desirable in the practice of the present process.

As more particularly shown in Fig. 2, the granulated material is fed at a measured rate from hopper H by means of a rotating auger conveyer 15, Figs. 2, 3 and 4, operating in a tube or casing 16, into a die charging housing 17, from 25 which the material passes into a series of lower die portions or members 18—18 passing in succession beneath the housing, the die portions being carried in a circular path on a relatively heavy rotary disk-like table or anvil member T. 30 A mating series of upper die portions 19—19, Figs. 2, 3 and 5, is carried in synchronism with lower die portions 18—18 by an upper die-carrier member 20, table T and die-carrier 20 being 35 rotatively supported at a slight angle to each other as shown particularly in Fig. 3 so that, as the members rotate together, the die portions 18 and 19 pass alternately from a relatively widely separated position as seen at the left in Fig. 3 to a closed position as seen at the right. The 40 material introduced into the lower die portions 18 by housing 17 is accordingly trapped, during the rotation of the members, between the die portions 18 and 19, and subjected to heavy pressure as the dies close. As the dies pass back 45 toward the starting position at the left of Fig. 4, the finished briquettes are dislodged and removed from the dies 18 by means of ejecting plungers 21—21 which are projected upwardly into dies 18 at appropriate times. Plungers 21—21 also 50 55

serve in the charging operation to preliminarily compact the material to insure a proper density thereof and to eject any excess in order to avoid undue pressures and stresses in the mechanism when the dies are closed.

Table T and die carrier 20 may be driven in any suitable manner, in the present instance from a motor 22, Fig. 2, through a drive shaft generally designated as 23, intermeshing gears 24 and 25, and a countershaft 26, the latter carrying gears 27 and 28 engaging, respectively, gears 29 and 30 fixed with die carrier 20 and table T. The material feeding auger 15 is also driven from motor 22, a gear 31 on the upper extremity of shaft 23 driving, through a gear 32, a combination shaft 33 carrying a sheave 34, driving, through a belt 35, an auger drive pulley 36.

Sheave 34 is adjustable in effective diameter, and furnishes a means of varying the speed of drive of auger 15, this adjustment being effected through a load responsive device 37 interposed in drive shaft 23, and a power relay 38 controlled thereby, as will appear more fully.

Turning particularly to Figs. 2 and 3, the machine is built upon and largely housed by a frame comprising upper and lower L-shaped sections 39 and 40 held together by suitable means such as through bolts 41-41 and 42-42, Fig. 4, the sections being so placed together as to provide a closed and an open side as particularly apparent in Fig. 2. Bolts 41-41 extend through tubular columns 43-43 for substantially rigidly maintaining the desired spacing between the frame sections at the open side thereof. The frame castings themselves are in contact with each other at the closed side, and effectively resist the pull of bolts 42-42. The frame is massively constructed, and reenforced at 44 and 45, Fig. 3, against the heavy stresses it has to resist, and by providing the structure with an open side, Fig. 3, ready access to actuating elements of the machine is available to attendants during its operation or otherwise.

Table T is carried by a large anti-friction bearing having a lower race 46, supported on lower frame section 40, a series of rolls or other anti-friction elements 47-47, preferably carried upon a spacing spider or other retainer 48 providing a series of fingers 49-49 upon which the rolls are journaled, and an upper race 50 upon which the table rests. This provides an exceptionally solid support for the table against the weight thereof and the considerable thrust reactions arising from the compressing of the briquettes.

Spider member 48 provides an upper groove 51 into which lubricant, from a suitable source not shown, is discharged from a nozzle 52, the lubricant discharging through ports or oil holes 53 onto fingers 49 and race 46, lubricating thoroughly. The periphery of the bearing is enclosed by a housing 54 of sheet metal or the like to prevent the entrance of dirt, escape of lubricant, or other undesirable results which might follow from leaving it exposed.

The table itself comprises a massive ring-like portion 55 closed at its upper side, and connected by a web 56 with a central hub portion 57, the hub being journaled for rotation about a pilot or column 58 projecting upwardly from frame portion 40, and preferably removably fixed therewith by bolts or the like 59. A bushing 60 is preferably interposed between column 58 and hub 57, and, for preventing undesired upward displacement of the table, a cap portion 61 is fixed to the top of the column by screws or the like 62 and pro-

jects laterally thereof to engage a portion of bushing 60.

The table carries a die-holding ring 63, fixed thereto by suitable bolts or the like 64, the ring being provided with a series of openings in which are placed die portions 18. The dies may rest upon spacers 65 interposed between them and the upper face of ring portion 55 of the table, these spacers giving a larger bearing on the table against the heavy pressures developed than would the bottoms of the dies themselves. Furthermore, they may be made interchangeable with others of different thicknesses to give an adjustment of the position of the dies.

For holding the dies down in ring 63 a plate 66 is superimposed thereon, engaging the mouths of the dies at 67, and held in clamping relation thereto by screws or the like 68. Plate 66 is continuous for a substantial distance inwardly from the periphery thereof, with the exception of the openings for the dies 18 and is substantially flush with the mouths of the dies so that surplus material struck from the dies will be carried on the plate. The plate also forms a lower closure for above mentioned feed housing 17, for supporting therein comminuted material in position to drop into die portions 18.

Plate 66 is spaced above ring 63, as shown in Fig. 3, by its engagement with die portions 18, and the ring has, exteriorly of the periphery of the plate, and spaced therefrom, an upstanding rim 69, forming with the plate edge an orifice 70 through which a strong draft of air, or suction, is maintained during the operation of the machine. Material left on plate 66 by operation of the charging mechanism finds its way, under the urge of centrifugal force, vibration, etc., to the edge of plate 66, where it is drawn into the orifice.

The material passes beneath the plate, about the die portions 18, and over and through a shield 40 or funnel 71, which directs it into the hollow interior 72 of above mentioned pilot 58, the lower end of which is in communication with a duct 73 leading to an exhaust fan 74, driven by any convenient means such as for example as a motor 75, Fig. 1, and a belt 76. The air and entrained material is discharged from the fan through a pipe 77 leading to a centrifugal, or other suitable extractor 78 where the material is extracted from the air and returned to hopper H.

A certain amount of very fine material is likely to be forced down between the ejecting plungers 21 and their bores in die portions 18, into bores 79 in table portion 55, and this is also extracted by the above described system, a series of ducts 80 admitting air to bores 79, and another series of ducts 81 communicating with a space 82 between ring portion 55 and hub 57, which is also exhausted by fan 74 through a plurality of ports 83-83, communicating with the space 72 within pilot 58. A shield 84 closes the space 82 from anti-friction bearing 47, and lubricant is prevented from being drawn into ports 83 by means of a packing element 85, on the shield, running on an enlarged base portion 86 of pilot 58. Lubricant is also prevented from being drawn from the pilot bearing by a packing element 87, the lubricant being supplied to the bearing through a pipe 88, and the excess draining away through a drilled or other suitable passageway 89 to the floor of frame portion 40 to be recovered or suitably disposed of. A duct 90 is provided to dispose of lubricant deposited outside of race 46.

Plungers 21 have enlarged shank portions 91 guided in bores 79, the shanks being provided 75

with suitable rack teeth 92, Fig. 4, engaging pinions 93 carried on shafts 94 journaled in ring portion 55 of table T, and also in bushings 95 suitably fixed in portion 55 as by threads 96, the shafts having arms 97 fixed thereon outside of table T and carrying suitable cam-follower rolls 98 journaled on pins 99 fixed with the arms, the rolls being positioned and arranged to run on a cam track 100 fixed with lower frame portion 40 in any suitable manner. A complementary cam track portion 101, Fig. 2, may be used to insure positive downward movement of the rolls and plungers at the proper times.

Above mentioned gear 30 is fixed with the table structure, in the present instance by screws 102—102, engaging ring member 63. The drive is thus transmitted in the most direct manner to the elements in which the torque reaction, or driving resistance arises, namely the die portions 18.

Die carrier 20 comprises a ring-like casting or member having die portions 19—19 suitably fixed therewith, the ring being fixed with a stem or journal 103 carried in a bearing portion 104 of upper frame member 39, a bushing 105 being interposed between the bearing and journal, and downward movement of the journal being prevented by a thrust element such as the lock nut 106 embodying a series of slots 107, nut 106 rotating in contact with a flange portion 108 of the bushing provided for this purpose. A pin 109 or other suitable safety locking means may be provided engaging slots 107 and 110—110 in the stem to prevent accidental displacement of the nut. The ring is preferably firmly held on the stem by screws or the like 111—111.

The major thrust reactions on ring 20 are upward, and for resisting these, ring 20 engages the lower race 112 of a large anti-friction bearing having a series of rolls 113—113 journaled on the fingers 114—114 of a spider 115 or other suitable retainer or other means for keeping the rolls properly spaced, or facilitating assembly. The upper race 116 of this bearing bears against the under side of frame 39, and transmits the upward thrust thereto.

Lubricant is introduced to the bearing through a pipe 117 for insuring proper lubrication thereof, and after passing through the same, finds its way to a trough 118 on the outer rim of ring 20 from which it flows to gear 29 in the vicinity of gears 27 and 28. Thorough lubrication of these main driving gears is thus obtained, and the spent lubricant finally drops to the floor of frame 40 and is discharged through above mentioned port 90. Gear 29 is attached to a flange portion 119 forming a part of above mentioned trough 118 by suitable means such as screws 120—120.

Die portions 18 are provided with flanges 121—121 which are seated as shown in suitable recesses in ring 20, and the flanges are engaged by strap members 122—122 held in clamping relation thereto by screws 123—123 threaded in ring 20. In this way the dies may be made of simple form for ready fabrication of hard material, while avoiding any difficulty in mounting them in the machine.

The upper anti-friction bearing preferably has a shield or housing 124 for excluding dirt, retaining lubricant, etc., similar to above mentioned housing 54.

As clearly apparent in Figs. 2 and 3, pilot 58 and stem 103 are not coaxial, but are arranged at a slight angle to each other, so that, as table T and die carrier 20 are rotated through gears

27, 28, 29, 30, die portions 18 and 19 pass from a relatively widely separated position, providing room for a feeding means, as shown at the left in Fig. 3, to a closed, or interfitting relation, as seen at the right of this figure, the latter resulting in a compression of material trapped between the dies, the pressure obtainable by this novel mechanism being so great that certain of the bituminous constituents of the material are expressed from the particles and act as a binder 5 to unite the material and prevent appreciable disintegration of the briquettes during storage and handling.

Obviously the amount of effort required to turn table T and carrier 20 will vary with the amount of material trapped between the die portions as the members rotate, and advantage is taken of this fact to regulate the feed of material to the dies so as to insure a sufficient and uniform hardness in the finished briquettes and operation of the machine substantially up to its maximum capacity, and to avoid developing excessive pressures and stresses in the mechanism. This is accomplished, as above briefly outlined, by varying the speed of auger 15 in accordance 20 with the amount of torque necessary to turn the table and die carrier.

Motor 22, Fig. 2, drives the table T etc. through above mentioned torque responsive element 37, gears 24 and 25, shaft 26, and gears 27 and 28, 30 shaft 26 being journaled at its upper end in a bearing portion 125, Fig. 3, of upper frame member 39, and at its lower end, beneath gears 27 and 28, in a bushing 126 carried in frame portion 40, gear 25 having a thrust portion 127 for 35 carrying the weight of shaft 26 and its attached parts. A chamber 128 may be arranged in the bushing to contain a quantity of lubricant, if desired. Gears 27 and 28 may be fixed with shaft 26 in any suitable manner, pins 129—129 40 being shown as passed through the gears and shaft and a key 130, Fig. 4, being seated therebetween to form a positive connection.

Gear 25 may have a tapered hub portion 131 bored to fit a correspondingly tapered portion on shaft 26 as shown, and a nut 132 threaded on a reduced stem 133 presses the gear on the shaft, a spacer 134 and a cam plate 135, for a purpose to be presently apparent being interposed between the nut and gear. A key 136 may be seated in the shaft and gear if desired. Gears 24 and 25 are enclosed in a housing 137, Fig. 5, having an upper closure 138 for protecting the mechanism from dirt, or the like, and carrying certain other mechanism to be later described. Housing 137 is fastened to frame member 39 by suitable means (not shown).

Drive shaft 23 comprises a portion 139, which may be a part of the motor shaft, and a portion 140, journaled in a bearing 141, carrying above 60 described gears 24 and 31, the portion 140 being coupled to portion 139 by means of the torque responsive coupling 37.

Coupling 37 comprises a sleeve portion 142, fixed with shaft portion 139 by means of a pin or the like 143, the sleeve opening out into a housing 144, in which is journaled at 145, for a limited amount of independent movement, the lower end of shaft 140. The shaft 140 is driven from rotation of housing 144 through a plurality of compression springs 146 and 147, Fig. 6, interposed between abutments 148 and 149, fixed with the interior of the housing, and wings 150 and 151 of a collar 152 fixed on the shaft 140 by suitable means such as a pin 153. Turning effort in shaft 70 75

- portion 139, opposed by resistance to turning in shaft portion 140 will therefore result in compression of springs 146 and 147, and relative angular displacement of the shafts. Within the capacity of the springs this displacement is a measure of the amount of torque transmitted by the coupling, and, in the present instance, of the amount of resistance offered by the material being compressed to rotation of the table T and carrier 20.
- 10 It is this displacement which is utilized in the present invention to regulate the rate of feed of material to the dies.
- For this purpose housing 144 is provided with an upper closure 154 fixed therewith by means of screws or the like 155 having upper cam portions provided with angular surfaces 156, engaging mating surfaces 157 on a cam element 158, which is maintained continually in the same angular relation with shaft portion 140, whereby the above mentioned angular displacement of casing 144 and shaft 140 will cause longitudinal, or lifting movement of cam portion 158. Shaft portion 140 carries a fly-wheel 159, fixed therewith in any suitable manner, as by a flange 160 and bolts or the like 161. Cam member 158 is clamped for rotative adjustment in a fitting or clamping member comprising upper and lower portions 162 and 163, united by screws or the like 164, portion 162 having a plurality of rods 30 or stems 165 slidable in bores 166 in fly-wheel 159, whereby clamping member 162-163, and accordingly cam 158 is constrained to rotate with the fly-wheel, but is free for axial movement relatively thereto. Rods 165, at their upper ends 35 bear against a plate 167 having a hub portion 168 slidable on shaft portion 140, and carrying by means of a suitable thrust bearing 169, a collar 170. A lever or bell-crank 171, pivoted at 172 on a bracket 173, fastened to the under side of housing 137 by screws or the like 174, has a forked portion 175 resting on collar 170 so as to partake of the up-and-down movement thereof, and this movement is transmitted to the feed regulating mechanism as follows:
- 40 Lever 171, through a link 176, actuates a lever 177 pivoted at 178 to a bracket portion 179 on a housing 180 of a hydraulic power relay structure to be presently described. The relay in the present instance duplicates in a shaft or plunger 181, movements imparted to a rod 182 pivoted at 183 to lever 177, plunger 181, however, being capable of exerting a very considerable force, while the effort required to move rod 182 is very slight. Plunger 181, through a rod 184 adjustable relatively thereto, the adjustment of which is maintained by a lock nut 185, and a bracket 186, pivoted to the rod at 187, shifts a sleeve 188 constituting the exterior of above mentioned combination shaft 33 axially, the sleeve being slidably 50 supported in a fitting 189, supported for convenience upon hopper H, and operative to change the effective diameter of sheave 34. The inner end of sleeve 188 is provided with a bushing 190 for supporting the sleeve on a shaft 191 constituting the inner portion of combination shaft 33.
- 55 Shaft 191 is driven from a shaft 192 journaled in bearing portions 193 and 194 in a housing 195 carried on gear housing 137, and supporting reservoir or housing 180. Shaft 192 carries and is 60 driven from above mentioned gear 32, and in turn drives shaft 191, in the present instance through a universal joint generally designated as 196, for permitting slight misalignment of the shaft. This provides for maintaining the tension on belt 70 75 35, above mentioned fitting 189 having an in-

wardly extending shank portion 189a slidable up and down in hopper H, and upwardly urged by a spring 189b connected thereto and suitably anchored to an upper portion of hopper H. As the effective diameter of sheave 34 is changed, as fully described below, fitting 189 is pulled down by the belt, or up by the spring, as the case may be, to maintain the belt tension within desirable limits.

Inner shaft 191 has fixed at its outer end a hub portion 197, Figs. 9 and 10 of a flange 198 of sheave 34, as by a pin 199. The other flange 200 has a housing portion 201 extending inwardly and connecting with a hub portion 202 slidably but non-rotatably engaging a splined portion 203 of inner shaft 191, and the axial position of flange 200 is controlled through sleeve 188, the sleeve having a fitting 204 fixed thereon and providing an enlarged portion 205 in which is arranged an anti-friction bearing 206, preferably of a type 20 adapted to sustain thrust as well as radial loads. This bearing bears in one direction against a shoulder 207 in fitting 204, and in the other direction against a shoulder 208 on hub 202, whereby a continuous thrust may be maintained 25 against flange 200 without interference with free rotation thereof. Bearing 206 may be maintained in place at times when there is no thrust by any suitable means such as a snap ring 209. As indicated in Fig. 9, the V-belt 35, when flange 200 30 is maintained close to flange 198, will be forced into a position close to the periphery of the flanges, which will result in a relatively high speed of the belt, and accordingly of auger 15, while with the parts in the position indicated in 35 Fig. 10, the belt will travel much nearer the center of the pulley, and the auger will operate much slower.

For permitting the closest possible approach to each other of flanges 198 and 200, the inner faces 40 thereof are made with alternate lands 210, and spaces 211, Fig. 11, the lands of one flange fitting into the spaces of the other when the parts are in closed relation as shown in Fig. 9. When the flanges are relatively widely separated, as shown 45 in Fig. 10, the belt may travel at least in part on the lands of both flanges.

Upon slightly greater separation of the flanges than that shown in Fig. 10, the belt will drop so that its inner edge or face rests on an idler pulley or roll 212 journaled on an inner extension 197e of hub 197, the flanges being in only light contact with the side faces of the belt, or entirely out of contact therewith, whereby a "loose pulley" effect is obtained, and the feed mechanism stopped 55 without stopping the motor 22, or shaft 191. During feeding operation idler roll 212 is wholly or partially enclosed in housing 201. It is maintained in axial position on hub extension 197e by means of a collar 213, fixed with the extension 60 in any suitable manner. A tension spring 214, Fig. 2, is engaged between housing 137 and a clamp or the like 215 on sleeve 188 for assisting in retracting the sleeve and pulley flange 200, the resulting constant pressure toward the right 65 as seen in Fig. 2 being of advantage in the operation of power relay 38.

It will now be apparent, assuming the machine to be running, that a balance will be maintained automatically with pulley 34 adjusted to feed 70 just enough material to cause a certain predetermined load on the motor 22. If this load is exceeded for any reason, springs 146 and 147 yield slightly, and the resulting displacement of housing 144 causes a raising of cam member 158, 75

this movement actuating lever 171 and causing a movement to the right of link 176, and accordingly of rods 182 and 184, permitting movement of pulley flange 200 away from flange 198, toward the condition shown in Fig. 10, slowing the operation of auger 15, and accordingly the feed of material. This will result in a reduction in the load on the parts to a desired value. If the load becomes too light the reverse operation of the parts takes place, moving the flange 200 toward the condition shown in Fig. 9, whereby the feed is increased. Close control of the load on the parts, and also of the degree of compression of the briquettes is thus obtained.

Power relay 38 may be of any suitable type which will permit relatively free movement of lever 171, while following movements thereof will correspondingly move rod 184, and which is capable of exerting a substantial amount of force upon the latter. A relatively simple arrangement is used in the present instance, above mentioned plunger 181, Fig. 7, being slideable in a guide portion 216 of housing 180, and having aligned therewith a stationary plunger 217, a sleeve 218 embracing both plungers in a substantially fluid-tight manner, but being freely slideable thereon. Fluid under pressure is introduced preferably at a substantially constant rate between the ends of plungers 181 and 217, preferably through a passageway 219 in plunger 217, forcing plunger 181 to the left as seen in Fig. 7 until its end uncovers, or partially uncovers a port 220 in the sleeve, the fluid escaping through the port and maintaining the plunger 181 in a position such that the port is maintained partly open. Movement of the sleeve to the left will carry port 220 past the end of plunger 181, closing the port whereupon the pressure fluid coming in at 219 will force the plunger to the left until the port is again open enough to permit the escape of fluid at a rate equal to that at which the fluid is introduced.

Movement of the sleeve to the right will increase the opening of port 220, whereupon fluid will escape from the sleeve faster than it is introduced thereto. The pressure between the plungers will accordingly be reduced, and allow spring 214 (Fig. 2) to move the plunger to the right until the port is again closed to permit the escape of fluid only fast enough to prevent a rise of pressure in the space between the plungers. It will be apparent that these operations will be accompanied by no substantial axial reactions in the sleeve 218, but that the force which may be developed in plunger 181 will depend largely upon the pressure available in the pressure fluid.

Fluid is contained in a reservoir in the bottom of housing 180, as more particularly shown in Fig. 5, and supplied to passageway 219 by means of a pump generally designated as 221, Fig. 7, driven with the other mechanism.

Fluid enters the pump through a passageway 222, Figs. 7 and 8, passing upwardly through a port 223, closed against return flow by a ball 224 or other suitable valve element, into a cylinder 225, preferably formed in a wall of housing 180, upon upward movement of a piston 226. Upon downward movement thereof the fluid flows out through a passageway 227 and a port 228, closed against return flow by a ball 229, into a bore 230 in which is fastened above mentioned stationary plunger 217. The plunger has a shoulder or collar 231 which is clamped against the inner wall of housing 180 by a nut or the like 232, and a groove 233 on plunger 217, within bore 230, provides a

passageway for fluid from port 228 and valve 229 around the plunger and into a port 234 leading from the groove into above mentioned passageway 219. Communication from the pump to the space within sleeve 218 is thus complete, regardless of the position in which plunger 217 happens to be placed in bore 230.

A by-pass valve 235 is arranged between pump 221 and plunger 217, having a port 236 which may stand, according to the position of the valve, aligned with, or transverse to a port 237 leading from a passageway 238, communicating with above mentioned bore 230, into housing 180. When the valve is in the latter position, the port 237 is, of course, closed, and the pump etc. functions as above described. When the valve is turned so as to open the bypass, fluid is pumped into bore 230, but is immediately exhausted therefrom together with any fluid in sleeve 218, through passageway 238 and port 237, allowing plunger 181 to move to the right until a stop portion 239 thereon rests against the end of plunger 217, which will allow the pulley flange 200 to take the above described position wherein belt 35 rests on idler, or loose pulley 212, so as to stop the feed of material by auger 15. Valve 235 may be controlled by a handle or stop lever 240.

Sleeve 218 receives its motion from rod 182 through a clevis 241 pivoted to a bracket 242 carried by the sleeve, and connection to lever 171 is effected by a clevis 243, preferably adjustably connected to rod 182, the adjustment being maintained by a lock nut 244. Other adjustments may be provided where necessary to facilitate obtaining correct relations of the parts to each other within the contemplation of the invention.

Pump piston 226 may be reciprocated in any suitable manner, preferably being upwardly urged by a spring 245 disposed in a counterbore 246 aligned with cylinder 225, and bearing against a collar 247 on the plunger, the upward movement being limited by a plug 248, threaded, or otherwise fixed in the upper part of the counterbore. The piston is downwardly actuated by a lever 249, Figs. 2 and 5, pivoted at 250 to an ear 251 supported on an upper portion of housing 180, the left end of the lever, as seen in the figures, being raised and lowered by a rod 252, preferably guided for sliding movement in apertured flanges 253 and 254 projecting from housing 180, and also in an apertured boss 255 on closure 138. The rod engages lever 249 at its upper end, and at its lower end rests on above mentioned cam plate 136, whereby rotation of the plate, with gear 25, etc., will cause rising and falling of the rod, and actuation of the pump 221.

It is desirable that the feed of material to the dies be as uniform as possible, and, to insure a dependable flow from hopper H to auger 15 agitators 256—256 Fig. 2, are fixed on a shaft 257 journaled in suitable bearings 258 and 259 in hopper H, and driven from a shaft 260 carrying above mentioned pulley 36, and constituting the final driving means for auger 15, a sprocket or the like, 261, being mounted on the shaft and driving, through a chain 262, a sprocket 263, mounted on shaft 257.

In spite of these precautions, periodic variations in the delivery of auger 15 are likely, and mechanism is provided for insuring an even loading of the dies regardless of the resulting "slugs" of material.

The auger delivers into the feed housing 17, Figs. 3 and 4, which is supported between the

table T and carrier 20, in the region of greatest opening of the dies, so that lower die portions 18 may pass below it, and upper die portions 19 may pass above. It is held from being displaced by 5 movement of the dies by means of an arm 264 extending outwardly into position to contact an abutment or bracket portion 265, fixed with one of columns 43 as shown, more particularly in Fig. 12, this portion taking any thrust developed in the 10 feed housing, but allowing a slight amount of free floating thereof. A second arm 266, Figs. 3 and 4, extends between the rotating members, and is journaled on a pin 267 fixed centrally of plate 66 as by a nut 268. The housing thus is held against 15 any tendency toward being dragged around by the table T.

In order to provide slight freedom of the housing, and to avoid straining auger housing 16, a flange or similar connection 269 is provided, a 20 sleeve 270 being interposed and extending into both the auger housing and the feed housing as shown, and a small amount of slack or looseness being allowed between the several parts. Auger housing 16 is fixed in any suitable manner with 25 the bottom of hopper H, which in turn is carried by a pair of arms 271—271, Fig. 2, fixed in any suitable manner with upper frame 39, and supporting the hopper by means of brackets or the like 272—272, suitably fastened to the hopper. 30 Arm 264 is urged downwardly by a spring 273, Fig. 12, bearing at its upper end against an abutment portion 274 of above mentioned bracket 265, a pin 275 extending upwardly from the arm and being slidably in a suitable aperture in the bracket 35 for guiding the parts, sufficient freedom being allowed to permit contact between the arm 264 and abutment 265.

Housing 17 is in the form of a curved elongated box having an opening 276, Fig. 4, extending over 40 the open tops of several of the lower die portions 18, so that the material in the housing may rest upon plate 66, and fall into the die portions as they pass beneath the opening. The material coming from the auger is thus deposited in the dies 45 and carried away thereby as the table rotates. Gravity alone, however, is not relied upon for filling the dies, a leaf or strike 277 being supported, normally in a downwardly inclined position in the direction of rotation of table T and dies 18, within 50 an opening 278 in the top of the feed housing, and terminating substantially at the end thereof in said direction of rotation. This is clearly shown in Fig. 14, and as apparent therein, material carried along on plate 66 in the direction of the 55 arrows will tend to be forced down by the inclined leaf, and struck off even with the tops of die portions 18.

During the cyclic variation in feed above mentioned, the amount of material may be momentarily greater than the capacity of the dies, and under these conditions the leaf is forced upwardly toward the dotted-line position in Fig. 14, the leaf being fixed on a rod 279 pivotally supported in bearings 280 and 281, Fig. 4, to permit such movement, and being urged downwardly by a torsion spring 282, anchored at one end in bearing 280, and at the other in collar 283, fixed with the rod 279. The leaf will "float" on the material, and tend to urge it into the dies, but if material is fed 65 momentarily at a rate greater than that at which the dies can take it away, the leaf will be pushed up by the material, which will accumulate under it in readiness for filling the dies a moment later when the supply from the auger is deficient. If 70 material continues to be fed too fast, the leaf will 75

be pushed up to the position indicated in dotted lines in Fig. 14, and the material will spill out over the top of housing 17, and find its way to plate 66 and return orifice 70. This will tend to iron out fluctuations in the feed of material to the dies. Under these conditions the material will be struck off level with the dies by wall 284 of housing 17. 5

Material of this type tends to vary somewhat in density owing to differences in fineness, moisture content, etc., and to compensate for this, the 10 material in the dies is given a slight preliminary compression. The capacity of die portions 18 with the material solidly packed is somewhat in excess of the amount of material in a finished briquette, and the preliminary compression either 15 compacts the material to the desired firmness before the heavy pressure is applied, or, if the material is already of sufficient firmness, forces some of it out of the die so that the charge, and consequently the final pressure on the material 20 and parts, is not excessive.

For this purpose a metering plate 285, Fig. 4, is pivoted at 286 and 287, respectively, to housing 17 and a bracket 288 extending therefrom, point 287 being adjustable if desired, and the adjustment 25 being maintained by a lock-nut 289. The plate is urged into firm sliding contact with plate 66, and serves to prevent the escape from the mouths of dies 18 of any material except in excess of that constituting a full charge. A spring 290, Fig. 13 30 compressed between plate 285 and an abutment 291 adjustable in a bracket 292 extending from above mentioned arm 264, Fig. 4, exerts a resilient pressure against the plate, but allows it to yield upwardly in the event that the upward pressure of 35 the material exceeds the pressure of the spring. Adjustment of abutment 291 permits adjustment of this pressure, and accordingly of the degree of preliminary compression of the material. The adjustment is maintained by a lock nut 293, 40 Fig. 13.

As previously pointed out, when dies 18 pass beneath plate 285, plungers 21 are raised to displace some of the material in the dies so as to compact, or preliminarily compress it, and if the 45 material as delivered into the dies is too loosely packed, plate 285 will resist the relatively low pressure developed, and will remain in the position shown in Fig. 14. On the other hand, if the material is reasonably tightly packed, the pressure developed by raising of the plunger 21 will raise plate 285 as indicated in dotted lines in Fig. 13, and some of the material will escape onto the surface of plate 66, and be swept by centrifugal force, vibration, and the like, into recovery 50 orifice 70. 55

The pressure developed in the die portions 18 during the final compressing of the material is very high, and, to avoid subjecting the actuating mechanism of plungers 21 to the resulting heavy 60 stresses, the shank portions 91 are arranged to rest at their lower ends upon upper race 50 of the lower bearing during the time that high pressure obtains in the dies, as clearly shown in Fig. 3, the race thus constituting a stop means for the 65 plungers in their outward movement. This may be conveniently done by providing a gap in the cam-track 100 in the region of high pressure in the dies. Since the rolls 98 are thus unsupported by the cam-track in this region, there is no resistance to downward movement of the plungers until race 50 is reached, and no possibility of 70 heavy stresses being imposed on the plunger actuating parts.

In operation, the material to be briquetted is 75

fed into bin B, Fig. 1, and dried sufficiently for the purpose in drier D. It is then conveyed by conveyor C to pulverizer P in which it is reduced to a uniformly fine state, the material then being raised into hopper H by elevator E. The granulated material is fed between the die portions 18 and 19 by auger conveyor 15, the rate of feed being governed by the torque resistance developed in the compressing mechanism, and appearing in the drive-shaft 23, the torque responsive coupling 37 regulating the effective diameter of the feed drive pulley 34 through the power relay 38.

In this way the feed of material to the dies is automatically kept at a rate which will result in the desired degree of compression in the material, and excessive stresses in the machine are avoided.

Pulsations in the rate of feed due to the action of auger 15 are compensated for by the "floating" of leaf or strike 271, the leaf rising to accommodate material fed momentarily in excess of the capacity of the dies. In the event that the excessive feed continues the strike rises sufficiently to allow the excess material to be spilled out through opening 278.

Beyond the strike the material is subjected to a preliminary compression against the yielding plate 285 by a rise of plungers 21, this serving to compact the material to a uniform density prior to the final compressing process, or if the material is already of proper density, forcing the plate upwardly, and allowing the excess to escape over the surface of plate 66. Material so discharged, or leakage is recovered through orifice 10 at the edge of plate 66, and through ducts 81, and transferred by the air blast maintained by fan 14 to extractor 18, and returned to hopper H. Plungers 21 are raised and lowered from rolls 98 running on cam-track 100 of suitable contour to raise and lower the rolls at the proper times, and the correct amounts to perform the various functions.

At about the point "B", Fig. 4, the plungers are gradually raised in order to eject the finished briquettes from the dies, and as the raised briquettes encounter the curved surface 294 of housing 11 they are deflected into chute 295, and conducted to elevator E' to be disposed of.

Chute 295 has an opening 296 covered by a grid or series of rods 297, any fragments, dust or the like which may escape the orifice 10 dropping through the opening so that only clean whole briquettes are finally delivered from the machine.

The feed of material to the dies may be stopped at any time without shutting down the machine by suitably setting by-pass valve 235 by means of stop lever 240.

For assisting in clearing the plate 66 a scraper 298 is arranged to form a continuation of surface 294, being supported from feed housing 17 at one end, and extending substantially in a spiral path and being fixed at its other end to the inner end of arm 266. Any particles not affected by centrifugal force, or otherwise urged toward the edge of the plate and orifice 10 are positively scraped by this member toward wall 294 whence they are directed to orifice 10 or chute 295.

Suitable expedients are provided for lubricating the parts, excluding dirt and the like, and for adjusting the relations of the various operating elements to insure proper coordination thereof.

It is understood that variations of the structure are contemplated, and that the invention is not limited to the specific mechanism shown and

described, or in fact in any manner except as set forth in the annexed claims.

What is claimed as new, and desired to be secured by Letters Patent of the United States is:

1. In a briquette making machine, upper and lower complementary die portions arranged to be moved alternately apart and together, load responsive means arranged to so move said die portions, means for charging said die portions with material to be formed into briquettes including a feed housing so located as to maintain a body of material in position to enter the lower die portion when presented to said housing, means for feeding material to said housing, and variable speed driving means for the feeding means, there being connections from said load responsive means for adjusting said driving means in accordance with the force necessary to move said die portions.

2. In a briquette making machine, upper and lower complementary die portions arranged to be moved alternately apart and together, means arranged to so move said die portions, means for charging said die portions with material to be formed into briquettes including a feed housing so located as to maintain a body of material in position to enter a lower die portion when presented to said housing, means for feeding material to said housing, means for presenting and removing die portions from beneath the housing, and means for relieving the housing of excess material fed by the feeding means including a strike positioned to direct material into the die portions as they pass beneath said housing and to strike it off substantially even with the margins of said lower die portions.

3. In a briquette making machine, upper and lower complementary die portions arranged to be moved alternately apart and together, means arranged to so move said die portions, means for charging said die portions with material to be formed into briquettes including a feed housing so located as to maintain a body of material in position to enter a lower die portion when presented to said housing, means for feeding material to said housing, means for presenting and removing die portions from beneath the housing, and means for absorbing fluctuations in the rate of feed of material to the housing for substantially uniform charging of said dies including a strike yieldably mounted and positioned to direct material into the die portions as they pass beneath the housing and to receive the upward thrust of said material so as to yield away from said die portions in the event of a momentary excess of material in said housing over the capacity of the die portions.

4. In a briquette making machine, upper and lower complementary die portions arranged to be moved alternately apart and together, means arranged to so move said die portions, means for charging said die portions with material to be formed into briquettes including a feed housing so located as to maintain a body of material in position to enter a lower die portion when presented to the housing, means for feeding material to said housing, means for presenting and removing die portions from beneath the housing, yielding means mounted and positioned to direct material into the die portions as they pass beneath the housing and to receive the upward thrust of said material, said means being arranged to yield away from said die portions to a position to allow escape of material from the housing in the event of an excess of material in

- the housing, and means for recovering material so escaping from the housing.
5. In a briquette making machine, upper and lower complementary die portions arranged to be moved alternately apart and together, means arranged to so move said die portions including a pair of juxtaposed rotors each carrying a set of die portions fixed therewith, the axes of the rotors being disposed at a slight angle to each other whereby to provide open and closed regions for the dies and to force them together for compressing material within the dies, means disposed in the open region and arranged for charging said die portions with material to be formed into briquettes, and means for ejecting finished briquettes from the dies operating in said open region in advance of the charging means.
6. In a briquette making machine, sets of complementary die portions arranged to be moved alternately apart and together, means arranged to so move said die portions including a pair of juxtaposed rotors each carrying a set of die portions fixed therewith, the axes of the rotors being disposed at a slight angle to each other whereby to provide open and closed regions for the dies and to force them together for compressing material within the dies, means disposed in the open region and arranged for charging said die portions with material to be formed into briquettes, and plungers arranged to be extended into the dies in accordance with the rotated position of the rotors to eject finished briquettes while the dies are passing through said open region and in advance of the charging means.
35. 7. In a briquette making machine, sets of complementary die portions arranged to be moved alternately apart and together, means arranged to so move said die portions including a pair of juxtaposed rotors each carrying a set of die portions fixed relatively thereto, the axes of the rotors being disposed at a slight angle to each other whereby to provide open and closed regions for the dies as the rotors rotate, and to compress material introduced into the dies for forming briquettes, means disposed in the open region and arranged for charging said die portions with such material, a closure disposed in said open region and arranged to temporarily close the charged die portions prior to closing thereof with their complementary die portions for forming briquettes and subsequent to charging thereof, and plungers arranged to be extended into the dies in accordance with the rotated position of the rotors so as to eject finished briquettes while the dies are passing through said open region and in advance of the charging means and again subsequent to charging of said dies so as to preliminarily compress material against said closure subsequently to charging of the dies by said charging means, said plungers being arranged to retract from said dies during the closing of said dies with each other for compressing material.
8. In a briquette making machine, set of complementary die portions arranged to be moved alternately apart and together, means arranged to so move said die portions including a pair of juxtaposed rotors each carrying a set of die portions, the axes of the rotors being disposed at a slight angle to each other whereby to provide open and closed regions for the dies as the rotors rotate, means disposed in the open region and arranged for charging said die portions with material to be formed into briquettes, a closure yieldably mounted in said open region and arranged to temporarily close the charged die portions prior to closing thereof with their complementary die portions, plungers arranged to be extended into the dies in accordance with the rotated position of the rotors for ejecting finished briquettes while the dies are passing through said open region and in advance of the charging means, and also so as to preliminarily compress material against said closure subsequently to charging of the dies by said charging means, said closure being arranged to yield in the event of abnormal preliminary compression to permit escape of a portion of the material from the die portions and to govern the amount of material allowed to remain in the charge, and means arranged to recover material escaping from said die portions.
9. In a briquette making machine, sets of complementary die portions arranged to be moved alternately apart and together, means arranged to so move said die portions including a pair of juxtaposed rotors each carrying a set of die portions, the axes of the rotors being disposed at a slight angle to each other whereby to provide open and closed regions for the dies as the rotors rotate, means disposed in the open region and arranged for charging said die portions with material to be formed into briquettes, and plungers arranged to be extended into the dies in accordance with the rotated position of the rotors so as to preliminarily compress material in said dies subsequently to charging thereof by said charging means and said plungers being arranged to recede in advance of closing of the dies for final compression of the material.
10. In a briquetting machine, a pair of rotatable disk-like members disposed in oblique relation to each other, mating die portions on said members positioned to be opened and closed for compressing material to be formed into briquettes by rotation of said members, means for rotating said members, means for feeding material to said dies when they are open for forming briquettes therein, and means in advance of said feeding means for removing briquettes formed in said dies.
11. In a briquetting machine, a pair of rotatable disk-like members disposed in oblique relation to each other, mating die portions on said members positioned to be opened and closed as said members rotate, means including a torque responsive element for rotating said members, means for feeding material to said dies when they are open for forming briquettes therein, means controlled by said torque responsive element for governing the amount of material fed by said feeding means, and means in advance of said feeding means for removing briquettes formed in said dies.
12. In a briquetting machine, a plurality of mating die portions, mechanism for opening and closing said die portions for forming briquettes therein, means including a load responsive element for driving said mechanism, means for feeding material to said die portions to be compressed, and means controlled by said load responsive element for governing the amount of material fed by said feeding means in accordance with the resistance of said material to operation of said die portions.
13. In a briquetting machine, a series of dies providing upper and lower portions arranged to be opened and closed in relation to each other in the operation of said machine, ejecting plungers arranged to be extended into said lower die portions for removing finished briquettes there-

from, mechanism for feeding an excess amount of comminuted material into said lower portions when said die portions are open, a yieldable closure element supported between said die portions and arranged to scrape some of said excess material from said portions before closing of said dies, and mechanism for introducing said ejecting plungers into said lower die portions while said closure is in position over said lower die portions for preliminarily compacting said comminuted material, said closure element being arranged to yield in the event of excessive preliminary compacting in said die portion to provide for the escape of the remainder of said excess material whereby a correct charge of material will be placed in each die regardless of variations in density of the comminuted material as delivered to the die portions.

14. In a briquetting machine, a series of dies supported for movement in a continuous path and providing upper and lower portions separated at certain points in said path and closed together at other points, ejecting members arranged to be extended into said lower die portions to expel finished briquettes therefrom at one point in said path, mechanism for feeding comminuted material into said lower portions at another point in said path, a yieldable closure element supported between said die portions and arranged to scrape excess material from said portions at a subsequent point in said path, and mechanism for introducing said ejecting members into said lower die portions during the period while said closure element is over said lower die portions for preliminarily compacting said comminuted material, said closure element yielding in the event of excessive preliminary compacting in said die portion to provide for the escape of a portion of said comminuted material.

15. In a briquetting machine, a series of dies providing upper and lower portions arranged to be opened and closed against each other in the operation of said machine, ejecting plungers arranged to be extended into said lower die portions for removing finished briquettes therefrom, mechanism for feeding comminuted material into said lower portions when said die portions are open, a closure element supported between said die portions and arranged to scrape excess material from said portions before closing of said dies, and mechanism for introducing said ejecting plungers into said lower die portions after the introduction of material thereinto, and while said closure is in position over said lower portions, for preliminarily compacting said comminuted material prior to final compression between said die portions.

16. In a briquette machine, a series of dies providing complementary portions arranged to be opened and closed in relation to each other in the operation of the machine, mechanism having portions arranged to be extended into certain of said die portions for removing finished briquettes therefrom, means for feeding comminuted material into said dies when said die portions are open, and a closure element supported between said die portions and arranged to scrape excess material from said portions before closing of said dies, said mechanism including means for preliminarily compacting against said closure element comminuted material introduced into said dies prior to the final compression between said die portions.

17. In a briquette making machine, a plurality

of mating die portions, mechanism for opening and closing said die portions to a predetermined definite closed relation to each other, for forming briquettes of predetermined definite and uniform size, means for charging the dies with material to be compressed and means governed by the density of the briquettes being formed for predetermining the amount of material in each charge with a sufficient degree of accuracy that the finished uniform sized briquettes will have a substantially uniform density.

18. In a briquette making machine, a pair of rotatable disk-like members disposed in oblique relation to each other, mating die portions on said members positioned to be opened and closed for compressing material to be formed into briquettes by rotation of said members, means for rotating said members, means for feeding material to said dies when they are open for forming briquettes therein, plungers associated with the die portions on one of said disk-like members, mechanism arranged for extending the plungers into the die portions at predetermined positions in the rotation of said disk-like member for operating upon material in the die portion, and means for feeding material to the die portions when they are open.

19. In a briquetting machine, a frame, an inclined rotatable table mounted in the frame and having a die member therein, means for delivering comminuted material into said die member, a plunger in the die member, means for intermittently actuating the plunger to control the quantity of material in the die member, an inclined rotatable die carrier mounted in the frame above said table and having a die member positioned to register with the die member in the table to trap and compress material therein, and means associated with the frame for rotating said table and carrier.

20. In a briquette making machine a plurality of mating die portions, mechanism for opening and closing said die portions for forming briquettes therein, means for charging the dies with material to be compressed and plungers arranged to be introduced into the dies during the cycle of operation, mechanism for so actuating the plungers, stop means for limiting the movement of the plungers out of the dies, and said actuating mechanism being arranged to release said plungers during the period that the dies are closed for compressing the briquettes, whereby the actuating mechanism is relieved from supporting the plungers against the heavy pressures then obtaining in the dies.

21. In a briquette making machine a lower substantially L shaped frame member and an upper inverted L shaped member, the vertical portions of the L shaped members being united, and the horizontal portions extending forwardly to provide a substantially C shaped frame, an inclined rotatable table mounted in the frame, an inclined rotatable die carrier mounted in the frame above the table, a set of dies fixed with the table, a set of mating dies fixed with the die carrier, said table and die carrier being juxtaposed whereby to provide open and closed regions for the dies and to force them together for compressing material within the dies, said open region being disposed remote from said vertical portions of said L shaped frame members, means for delivering comminuted material into said die members disposed in said open region between the dies, and means on the frame for rotating said table and said die carrier.

22. In a briquetting machine a pair of rotatable disk-like members disposed in oblique relation to each other, mating die portions on said members positioned to be opened and closed as said members rotate, means including a load responsive element for rotating said disk-like members, means for feeding material to said die portions

to be compressed, and means controlled by said load responsive element for governing the amount of material fed by said feeding means in accordance with the resistance to rotation of said disk-like members.

JOHN F. CRAWFORD.
